(57) **CLAIM**

The ornamental design for a transaction card, as shown and described.

DESCRIPTION

FIG. 1 is a front perspective view of a transaction card having a transparent portion, showing the new design; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an example front view thereof further illustrating a transparent nature of the transparent portion of the transaction card;

FIG. 9 is an enlarged view of callout region 9 of FIG. 8; FIG. 10 is a front perspective view of a transaction card, showing the new design;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is a bottom view thereof;

FIG. 17 is an example front view thereof further illustrating a non-transparent nature of the transaction card; and,

FIG. 18 is an enlarged view of callout region 18 of FIG. 17. The broken line showing of the figures illustrates portions of the transaction card that form no part of the claimed design. The dash-dot-dash lines are included to show the enlargement portion of the transaction card and form no part of the claimed design.
